UNITED STATES PATENT OFFICE.

CHARLES BRAUN, OF BROOKLYN, NEW YORK.

STORAGE AND DISPENSING APPARATUS.

Application filed January 20, 1921. Serial No. 438,590.

To all whom it may concern:

Be it known that I, CHARLES BRAUN, a citizen of the United States, and resident of borough of Brooklyn, county of Kings, 5 State of New York, have invented certain new and useful Improvements in Storage and Dispensing Apparatus.

This invention relates to improvements in storage and dispensing apparatus and the 10 principal object of the invention resides in the provision of a device particularly adapted for the storage of flour, sugar and similar granular or pulverized material.

Another object of the present invention, 15 is to provide a dispensing attachment for the device designed to discharge a given quantity of the contents of the receptacle at a single operation.

Still another object of the invention resides in the provision of a dispensing means 20 which may be manipulated to discharge double the quantity at the desire of the user.

A still further object of the invention resides in the provision of a sanitary container which will effectively exclude dust and other foreign matter from the contents and to provide a dispensing means which may be manipulated without bringing the 30 operators' hands in contact with the material being used.

With these and other objects in view the invention consists of a novel construction, combination and arrangement of parts 35 which will be fully set forth in the following specification, claimed and illustrated in the accompanying drawings in which:—

Fig. 1 is a vertical sectional view through this improved storage and dispensing device.

Fig. 2, is a horizontal sectional view on line 2—2 of Fig. 1.

Fig. 3, is a horizontal sectional view on line 3—3 of Fig. 1.

Fig. 4 is a fragmentary sectional view 45 through the lower end of the storage and dispensing device, a portion thereof being in section, taken at right angles to Fig. 1 and illustrating a flour sifter attached thereto and

Fig. 5, is a top plan view of the storage receptacle.

Referring to the drawings in detail the 50 numeral 10 designates the body of the receptacle which comprises a cylinder provided at its lower end with an off set flange

11 for a purpose to be more fully herein-after described.

The upper end of the cylinder is partially closed by a cover section 12 which is provided with an opening arranged axially of the cylinder 10 to receive the shaft 13. An angularly extending handle 14 is arranged at the upper end of the shaft 13, and a movable cover section 15 is pivotally mounted on the shaft for co-operation with the cover member 12 for completely closing the upper end of the storage chamber, 16. Mounted near the lower end of the cylinder is a transversely extending wall 17 which is **U** shaped in cross section and has its bight portion disposed upwardly and provided with a central opening 17' in which the lower end of the shaft 13 is journaled.

The upper end of the wall 17 defines the 75 lower terminal of the chamber 16 and is rotatably mounted on the shaft 13 and resting upon the bight portion of the wall 17 is a disk 19 provided with radiating discharge slots 20 arranged diametrically opposite each other in such a manner that when said slots lie parallel with the legs of the wall 17 they will be completely closed to prevent the discharge of the contents of the storage chamber 16 into the dispensing cups or chambers 21 and 22 which are arranged directly beneath the chambers 16 as clearly illustrated in the drawings.

In order to close the under sides of the chambers 21 and 22 suitable trap members 90 23 and 24 are hinged as at 25 and 26 directly beneath the lower edges of the legs of the **U** shaped wall 17. As shown these trap members are arranged to drop downwardly so that the entire contents of each 95 of the dispensing chambers may be discharged.

In order to control the filling and the discharge of the dispensing chambers the shaft 13 is provided with a cross member 100 27 which is arranged to engage a resilient stop 28 secured to the plate 19 and it will thus be seen upon rotating the handle 14 the shaft 13 will be turned thereby imparting rotary motion to the plate 19 when 105 either leg of the cross member 27 engages the stop 28. Suitable co-operating stop pins 29, 30 and 31 are arranged on the plate 19 and at opposite sides of the cylinder 10 respectively, and it will thus be seen 110 that the pin 30 engaging the pin 29 will stop the rotation of the plate in such posi-

tion as to close the slots 20 and prevent the discharge of the contents of the chamber 16 into the chambers 21 and 22.

The operation of the traps 23 and 24 is controlled by a substantially V shaped member 32 which is loosely mounted adjacent the lower end of the shaft 13 and carries a pin 33 which is adapted to be engaged by an angularly extending arm 34 connected 10 to the lower end of said shaft. The arms 32 of the V shaped member are adapted to ride upon the under side of the trap members 23 and 24 and it will be seen that when said member is turned in the position illustrated in Fig. 3 the member 24 will be permitted to fall thus allowing the contents of the chamber 22 to be discharged.

In operation the storage chamber 16 is filled with the desired quantity of material 20 and upon turning the cover to closed position it will be seen that the indices 35 will assume proper position so that upon moving the handle 14 in a counter clock wise direction or as indicated by the top the direction marked "To fill" the cross member 27 will contact with the resilient element 28 and move the plate 19 into such position that the slots will be opened thus permitting the dispensing chambers 21 and 22 to be 25 filled.

Upon reversing the direction of movement of the handle and rotating the same as indicated by the arrow on the top marked "To measure" it will be obvious that the 35 opposite arm of the cross section 27 will engage the resilient element 28 and swing the plate 19 into such position that the slots 20 will be closed by the bight portion of the wall 17.

Upon continual rotation in the same direction it will be obvious that the arm 34 will contact with the pin 33 and rotate the V shaped member 32 into such position as to permit one or the other of the members 45 23 or 24 to drop and discharge the contents of its respective chamber. Upon continuing the movement of the handle until it lies in a plane with the mark on the top of the device "2 cups" the member 32 will be 50 moved to permit the opposite discharge

chamber to empty and thereby double the quantity will be deposited.

Should it be desired the flour sifter such as illustrated in Fig. 4 may be used and said sifter consists of an open ended cylinder 35 provided with a suitable sifting screen 36 over which an agitator 37 operates. While I have shown a particular type of sifter namely that shown and described in my co-pending application filed, January 20, 1921, Serial No. 438,589, it is to be understood that any type of sifter may be utilized without departing from the spirit or scope of the invention.

While in the foregoing there has been shown and described a preferred embodiment of this invention, it is to be understood that certain minor changes in the details of construction, combination and arrangements of parts may be resorted to 70 without departing from the spirit and scope of the invention as claimed.

What is claimed is:—

1. A device of the class described comprising a body having a storage chamber, a pair of measuring chambers beneath the storage chamber, a rotatable slotted plate dividing the storage from the measuring chambers and adapted when in one position to permit the measuring chambers to fill 75 from the storage chamber, hinged bottoms closing the measuring chambers and means for selectively opening or closing the hinged bottoms.

2. A device of the class described comprising a body having a storage chamber, a pair of measuring chambers beneath the storage chamber, a slotted plate separating the storage and measuring chambers, hinged bottoms closing the under sides of the 90 measuring chambers, means for turning said plate to permit the slots to open and allow the measuring chambers to fill simultaneously, means for selectively discharging the measuring chambers and a single 95 lever for operating the plate and the selective means.

Signed in the city, county and State of New York, this 18th day of January, 1921.

CHARLES BRAUN.
